UNITED STATES PATENT OFFICE

153,973

DESIGN FOR A POKER CHIP COUNTER

Robert D. Nelson, Chicago, Ill., assignor to Count-Rite Industries, Inc., Chicago, Ill., a corporation of Illinois

Application October 31, 1946, Serial No. 134,411

Term of patent 7 years

(Cl. D34—13)

To all whom it may concern:

Be it known that I, Robert D. Nelson, a citizen of the United States, residing at Chicago, in the county of Cook and State of Illinois, have invented a new, original, and ornamental Design for a Poker Chip Counter, of which the following is a specification, reference being had to the accompanying drawing, forming part thereof.

In the drawing,

Figure 1 is a top plan view of a poker chip counter, showing my new design;

Figure 2 is a side elevation thereof; and
Figure 3 is a reduced front elevation.

I claim:

The ornamental design for a poker chip counter, as shown.

ROBERT D. NELSON.
